United States Patent Office.

WILLIAM H. JOECKEL, OF NEW YORK, N. Y.

Letters Patent No. 92,533, dated July 13, 1869.

IMPROVEMENT IN BLACK-BOARDS.

The Schedule referred to in these Letters Patent and making part of the same.

To all whom it may concern:

Be it known that I, WILLIAM H. JOECKEL, of the city, county, and State of New York, have invented a new and improved Endless Black-Board; and I do hereby declare that the following is a full, clear, and exact description thereof, which will enable others skilled in the art to make and use the same, reference being had to the accompanying drawings, forming part of this specification, in which—

Figure 1 represents a front elevation of a frame, provided with my improved black-board.

Figure 2 is a vertical transverse section of the same, taken on the plane of the line x x , fig. 1.

Similar letters of reference indicate corresponding parts.

The object of this invention is to provide a black-board for schools, lecture-rooms, &c., which can be adjusted so that marks made upon its lower part can be elevated to be in sight of the whole audience, and so that such marks which are not used at a certain time may be concealed on the back of the board, to be brought forward whenever desired for further reference, and without shifting the frame.

The invention consists in arranging an endless belt, which has been treated by suitable ingredients, to retain and display chalk or other marks, and in fitting the same over horizontal rollers, hung in a frame, so that the belt can be readily turned for the aforementioned purpose.

A, in the drawing, represents a frame made of wood or other suitable material, of suitable size and form, and supported or suspended in suitable manner.

In the frame are arranged two rollers, B and C, over which an endless belt, D, is placed, said belt being blackened or otherwise so treated that chalk or other marks made upon it can be easily seen and readily removed.

The apron, or belt D is well stretched, so that it will be turned when, by means of a crank a , or otherwise, rotary motion is imparted to the lower or upper roller.

One of the rollers should lie in adjustable boxes b , which can be set, by means of screws c or otherwise, to keep the belt stretched.

When a high frame is used, the upper part of which cannot conveniently be reached, it will, with this arrangement, be easy to write on the lower part of the belt, and then to turn the roller so that the marks will be carried to the upper part of the frame, where they can best be seen.

Such marks as are not used can be carried to the back of the frame, without shifting the same, and can again be brought to the front whenever they are to be used.

This black-board arrangement will be much more convenient than the rigid board now in general use, and may be made much larger and higher without making it difficult to use.

Between the rollers a board, d , should be arranged on the frame, to give the belt a support while it is being marked.

A small plate, or platform, e , may be arranged on the frame to support chalk, sponge, &c.

I claim as new, and desire to secure by Letters Patent—

An endless black-board, consisting of the prepared belt D, fitted around rollers, substantially as described.

The above specification of my invention, signed by me this 20th day of January, 1869.

WM. H. JOECKEL.
